UNITED STATES PATENT OFFICE.

WILLIAM J. HAMILTON, OF NEWARK, NEW JERSEY.

COOLING APPARATUS

No. 898,921

Specification of Letters Patent. Patented July 21, 1908

Application filed July 19, 1907. Serial No. 384,567.

To all whom it may concern:

Be it known that I, WILLIAM J. HAMILTON, a citizen of the Dominion of Canada, residing in the city of Newark, county of Essex, and State of New Jersey, have invented a new and useful Improvement in Cooling Apparatus, of which the following is a specification.

This invention relates to cooling apparatus and more particularly to cooling apparatus designed for use in cooling the water or other liquid which is employed in motor vehicles propelled by explosion engines for the purpose of cooling the engine cylinders.

The invention may, however, be employed in other situations, and I do not limit myself to any particular use.

The main object of the invention is to produce a cooler or radiator of great efficiency, staunch and rigid in construction, and attractive design, at a minimum cost.

Reference is had to the accompanying drawings, forming part of this specification, in which similar characters of reference indicate corresponding parts in all the views.

In the drawings: Figure 1 is a front elevation showing a cooler embodying the present invention; Fig. 2 is an enlarged detail view in front elevation showing portions of two adjacent tubes and spacing members associated therewith; Fig. 3 is a sectional view on the plane 3—3 of Figs. 1 and 2.

In common with other coolers of the type to which the present invention relates, my improved cooler is provided with top and bottom chambers 1 and 2, the top chamber 1 being provided with a suitable inlet closed by a cap 3. Extending vertically between the chambers 1 and 2 are a plurality of tubes 4 for the passage of the water to be cooled.

The tubes 4 are spaced apart to approximately the extent indicated in Fig. 3 to permit the passage of air between them in the usual manner. These tubes 4 are of special construction, each being preferably formed

from a single piece of sheet metal, which is first corrugated on opposite sides of the median line, then folded on the median line to present a flattened portion 5 and bring the corrugations together so as to form, in effect, a series of separated tubes or passages 6. The edges of the piece of sheet metal, preferably copper or brass, are then united in a seam 7 with the formation of a comparatively wide flat portion 8 between it and the adjacent passage 6. Each of the tubes 4 is rendered comparatively stiff by the corruga-

tions formed in the metal of which it is made and may, therefore, be made of very light stock without making the tube too weak to withstand the strains to which it will be subjected. The tubes are set vertically between the top and bottom chambers 1 and 2 and are arranged as shown in Fig. 3, the seams of one-half of the tubes being disposed at the rear of the cooler and those of the other half being disposed at the front. The object of this arrangement is to bring the comparatively wide flat portions 8 of alternate tubes opposite the comparatively narrow flat portions 5 of the adjacent tubes, in this way bringing the passages 6 of one tube opposite the grooves 8' presented between the corrugations of the adjacent tube, and thus producing a sinuous air passage 9 between each pair of adjacent tubes.

To hold the several tubes 4 in proper relation and to impart stiffness to the entire cooler structure, spacers 10 are employed between the tubes, being soldered or otherwise suitably secured between the flat portions of the tubes at the front and rear of the cooler. These spacers 10 are preferably of the angularly corrugated construction shown in the drawings. The advantage of this angular form of corrugation is that more surface is thereby afforded for attachment of the spacers to the tubes than would be presented if the corrugation were of a different type.

The efficiency of the cooler is increased by the arrangement of the tubes to present sinuous air passages between the tubes. The effect of the sinuosity of the air passages upon the currents of air passing through them is to set up minor currents in the air as it passes through the passages, thereby bringing into contact with the walls of the water tubes the air which but for these minor currents would lie in the middle of the current as it passes through one of the air passages and, therefore, would not come in contact with the side walls of the water tubes. This effect is of considerable importance, owing to the non-conductivity of air. When no minor currents are set up in a body of air passing between the air tubes of a cooler of the type to which the invention relates, only a comparatively small proportion of the total amount of air which passes through the air passages can exert any cooling effect upon the liquid contained in the tubes, while the sinuous form of the air pas-

sages shown in the present construction results in the utilization of all of the air for cooling purposes.

As the individual water tubes are formed of corrugated metal and the spacers or separators between the tubes are very securely soldered to the tubes, the entire radiator structure is rigid and may be constructed of light weight material, thereby insuring both 10 cheapness and efficiency.

Having thus described my invention, what I claim as new and desire to secure by Letters Patent, is:

1. A cooler for liquids comprising upper and lower chambers connected by a plurality of liquid conduits, the side walls of which are corrugated longitudinally to form a plurality of spaced passages; said conduits having plane margins secured in lateral 20 spaced relation by separate corrugated spacers.

2. A cooler for liquids comprising upper and lower chambers connected by a plurality of liquid conduits each formed from a sheet of metal having longitudinal corrugations on each side of a median plane and folded along the center line of said median plane to bring said corrugations into register to form a tube having separate parallel liquid passages and plane margins; said 30 tubes being assembled so as to provide sinuous air passages between their external surfaces and having their plane margins secured in spaced relation by angularly corrugated spacers forming long bearings for said plane 35 margins.

In testimony whereof, I have signed my name in the presence of two witnesses.

WILLIAM J. HAMILTON.
